UNITED STATES PATENT OFFICE.

LEE J. LOOMIS AND EDWARD B. FURRY, OF UNION, NEW YORK, ASSIGNORS TO THE UNION FORGING COMPANY, OF UNION, NEW YORK, A CORPORATION OF NEW YORK.

SPRING PLATE.

Application filed March 21, 1924. Serial No. 700,914.

To all whom it may concern:

Be it known that we, LEE J. LOOMIS and EDWARD B. FURRY, citizens of the United States, residing at Union, in the county of 5 Broome and State of New York, respectively, have invented certain new and useful Improvements in Spring Plates, of which the following is a specification, reference being had therein to the accompanying 10 drawing.

Our invention relates to new and useful improvements in spring plates more particularly adapted for use in connection with vehicle springs, the principal object of the 15 invention residing in the provision of such a plate which may be easily connected to or disconnected from the vehicle without the assistance of skilled help and which will engage the under surface of the lowermost 20 leaf of the spring to strengthen the spring at the point of greatest strain or at the center point where the spring bolt usually passes through, the plate also by reason of its structure and the distribution of weight of 25 the metal of which it is composed preventing a sidewise swinging movement or weave of the spring.

Another object of our invention resides in 30 providing a longitudinally curved channel within the plate so as to conform to the longitudinal curvature of the spring with which the plate is used.

A still further object of the invention consists in forming the plate with upwardly 35 extending longitudinal flanges which engage the side edges of the spring thereby positioning the plate relative to the spring when assembling, the plate having, adjacent each longitudinal edge, spaced openings 40 to receive bolts or clips whereby the plate will be connected in position relative to the spring or to the spring assembly.

With the above and other objects in view, which will appear as our description proceeds, our invention consists in the novel details of construction, and arrangement 45 of parts, illustrated in the accompanying drawings and described in the following specification, and while we have illustrated and described the preferred embodiments of 50 the invention as they now appear to us it will be understood that such changes may be made as will fall within the scope of the appended claims.

In the drawings:

55

Fig. 1 is a side elevation.

Fig. 2 is a section on line 2—2 of Fig. 1.

Fig. 3 is a section on line 3—3 of Fig. 1.

Figs. 4 and 5 are top and bottom plans, respectively, of our plate.

60

Fig. 6 is a longitudinal section on the line 6—6 of Fig. 4; and

Fig. 7 is a transverse vertical section on the line 7—7 of Fig. 4.

65

In the drawings 1 indicates a portion of the vehicle frame commonly known as a shroud, this shroud being of inverted U-shape, as shown, and receives the uppermost portion of the longitudinally curved leaf spring 2 as quite clearly shown in the drawings. In the form illustrated in the drawings the spring extends transversely of the vehicle.

70

Our improved form of spring plate is indicated at 3, the upper surface of the plate, when in use, engaging beneath the lowermost leaf of the spring 2 and being of such a length as to extend a substantial distance to each side of the bolt 4 which passes vertically through the leaves of the spring at the center point. Upwardly extending flanges 5 are formed along the longitudinal edges of the plate and form therebetween a channel 6 for the reception of the lowermost leaves of the spring, the bottom of said channel being longitudinally curved to conform to the longitudinal curvature of the spring. At the ends 7 of the flanges 5 are of less height than the intermediate portions so as to allow spring clips, to be later described, of different lengths, to be used. An opening 8 is formed intermediate the ends of the plate to receive the head of the bolt 4 which connects the leaves of the springs at the center point.

75

Extending through the flanges 5, adjacent the ends of the plate, are the vertical openings 9 and extending through the flanges at the longitudinal centers thereof are the vertical openings 10.

80

The under surface of the plate is cut away as shown at 11 which leaves a space for the use of a wrench in assembling and at the corners 12 the under surface of the plate is cut away to form a flat bearing surface for the nuts used in assembling. The under surface of the plate is beveled from opposite ends toward the center thus

85

distributing and equalizing the weight of the material in proper proportions for uniform strength throughout its structure. Also, by forming the plate as described, the thickness of the metal being about even on all the different planes, the structure proper in shape and adequate in strength is provided for distributing the strains to which the spring is subjected evenly throughout the entire length of the spring.

In assembling or connecting the plate to the vehicle frame and spring we use the usual saddle clamp so commonly in use upon certain forms of vehicles as well as two spring clips of suitable length. The saddle clamp is indicated generally at 13 and in its well known construction has an opening 14 for the reception of the starting crank and downwardly extending bolts or legs 15 which will pass through the central openings 10 of the plate, the bolts or legs being exteriorly threaded to receive the nuts 16 which when in position will be received in the cut out portion 11 of the under surface of the plate said cut out portion 11 providing room for the use of a wrench in applying the nuts. As is shown the saddle clamp engages over the upper surface of the shroud 1 and the sides thereof overlap the side faces of the shroud. Spring clips 17 are positioned on opposite sides of the saddle clamp and the arms or legs of these clips extend through the openings 9 adjacent the ends of the plate. The arms or legs are exteriorly threaded to receive the nuts 18 and when in position the nuts will bear against the under surface of the plate and be received in the cut out corners 12 thereof. By reducing the height of the flanges 5 at points 7 spring clips of different lengths may be used thereby allowing for the use of our plate with springs employing different numbers of leaves. As shown the spring clips also extend over the upper surface of the shroud 1 and parallel with the side faces thereof.

We are well aware that springs have been connected to vehicle frames or shrouds by use of a saddle clamp and a clip yoke which extends beneath the lowermost surface of the spring, the clip yoke being nothing more than a very narrow plate or strip having openings adjacent the ends to receive the legs of the saddle clamp. With a construction such as this the spring is only supported at its transverse center line and therefore there is a tendency for the spring to swing relative to the frame or there would be a side weave of the body of the vehicle thereby causing the spring to break at the center. When using a plate such as we have provided the spring is strengthened and the swinging movement of the spring relative to the frame or the

side weave of the body relative to the spring is overcome thereby preventing breakage of the spring at the center point. Our improved form of plate is provided with a longitudinally extending channel to receive the spring and the bottom of this channel is longitudinally curved to conform to the longitudinal curvature of the spring. Upwardly extending side flanges are also provided which engage the side edges of the lowermost leaves of the spring and central openings are provided adjacent the longitudinal edges of the plate to receive the legs of the saddle clamp. The plate is of such a length as to extend some little distance to each side of the transverse center of the spring thereby supporting the under surface of the spring for quite a little distance and adjacent each corner there is an opening to receive the legs of spring clips which extend over the frame or shroud of the vehicle on opposite sides of the saddle clamp. It will thus be seen that we have provided a novel form of plate which supports and strengthens the spring and that said plate is supported not only adjacent the transverse center but adjacent each end whereby it is securely held in position and the spring is so held relative to the frame or shroud as to prevent side weave of the body or spring thereby not only preventing the tendency of the spring to break but at the same time it has been found, by actual experience, that the vehicle will ride much more smoothly thereby adding to the comfort of the occupant.

Having fully described our invention what we claim as new and desire to secure by Letters Patent is:

1. A spring plate comprising a bottom and upwardly extending flanges formed along the longitudinal edges thereof to form a channel therebetween, the ends of the flanges extending beyond the ends of the bottom and having openings therein.

2. A spring plate comprising a bottom formed of longitudinally spaced portions and upwardly extending flanges formed integral therewith, the flanges bridging the space between the bottom portions and forming a longitudinally extending channel.

3. A spring plate comprising a bottom formed of longitudinally spaced portions and upwardly extending flanges formed integral therewith, the flanges bridging the space between the bottom portions and forming a longitudinally extending channel and the ends of the flanges extending beyond the outer ends of the bottom and having openings therein.

4. A spring plate comprising a bottom formed of longitudinally spaced portions and upwardly extending flanges formed integral therewith, the upper surfaces of the bottom portions being downwardly curved

towards their outer ends and the flanges bridging the space between the bottom portions and forming a longitudinally extending channel.

5. A spring plate comprising a bottom formed of longitudinally spaced portions, and flanges formed integral with said bottom portions and spanning the space therebetween.

10. 6. A spring plate comprising a bottom

formed of longitudinally spaced portions, and flanges formed integral with said bottom portions and spanning the space therebetween, said flanges having openings therein to receive means whereby the plate may 15 be secured in position.

In testimony whereof we hereunto affix our signatures.

LEE J. LOOMIS.

EDWARD B. FURRY.
